FOLDING TABLE

Leslie H. Burlin, Valparaiso, Ind., assignor to Milton L. Sturm, Evanston, Ill., doing business as Milton Sturm & Company, Chicago, Ill.

Application October 19, 1942, Serial No. 462,645

9 Claims. (Cl. 311—80)

This invention relates to folding tables.

It is an object of the present invention to provide a collapsible or folding table which is so constructed that when folded the opposite sides are flat to facilitate storage of the table in a small space and to facilitate stacking of a plurality of such tables one against or on top of another in a minimum amount of space and without a likelihood of parts of one table marring or scratching parts of another table. This is accomplished by providing an arrangement wherein the links or legs of the table, which normally support the table, are collapsible in a position on the interior of the table, substantially entirely protected, whereby there are no links or levers projecting from opposite surfaces of the collapsed table.

It is a further object of the present invention to provide a collapsible table with a plurality of legs each of which consists of two or more links pivoted together and foldable from a position of toggle when the table is extended, to a position of substantial parallelism when the table is unfolded.

It is a still further object of the present invention to provide such a table with a simple and reliable means for preventing wobbling or movement of the links when and if a certain amount of play develops at the link pivots. As a result of this arrangement the table remains sturdy and does not tend to wobble even after there has been considerable wear and resulting developed looseness at the pivots of the links of the table legs.

The attainment of the above and further objects of the present invention will be apparent from the following specification taken in conjunction with the accompanying drawings forming a part thereof.

In the drawings:

Figure 1 is a sectional view through a table embodying the present invention, said table being in its unfolded position, said view being taken along the line 1—1 of Figure 2;

Figure 2 is a bottom plan view taken along the line 2—2 of Figure 1;

Figure 3 is a sectional view through the table in its folded position;

Figure 4 is a bottom view of the folded table, with a part of the table base broken away;

Figure 5 is an enlarged front view of the joint between two table legs, said view being taken along the line 5—5 of Figure 1;

Figure 6 is a sectional view taken along the line 6—6 of Figure 5; and

Figure 7 is a sectional view taken along the line 7—7 of Figure 5.

Like reference numerals indicate like parts throughout the various figures of drawings.

- 5 The table of the present invention has a table top 1 which, in the present instance, has been illustrated as circular although it is to be understood that the top may be of any other desired shape. Around the bottom side of the table top 1 there is a circular rim 2, as is usual in tables. The underside of the table top 1 is reinforced by three symmetrically spaced cross bars 5 and three radial bars 6 that are secured to the underside of the table top. The top of the table 15 1 is supported from a flat circular base 7 by three similar folding legs 9 of identical construction. Each leg includes an upper link 12 and a lower link 13 pivoted together and to the table top and base, respectively. For this purpose the link 12 consists of two similar wooden side members 14—14 rigidly secured together by a cross board 15. The three table legs are symmetrically spaced 120° apart about the center of the table. Since the three legs are of identical construction and are mounted in position in exactly the same manner, a description of one of the legs and the manner of mounting the same will suffice also for the other two. In order to pivot the side members 14—14 of a leg to the table 20 top the underside of the table top 1 is provided with a pair of spaced downwardly projecting lugs 17—17 that are rigidly secured thereto in any desired manner. A pivot or dowel pin 18 passes between one of the members 14 and the lug 17. A similar pivot pin passes between the other member 14 and the other lug 17, the two pivot pins 18—18 being in alignment. Each pivot pin 18 is journaled also in a bar 19 secured to the underside of the table top 1. The link 12 25 is thus pivoted to swing about the pins 18 as a center. The lower link 13 consists of a pair of similar members 20—20 joined together by a board 21 to form one unitary structure. The members 20—20 embrace the members 14—14 and are pivoted thereto by pivot or dowel pins 22—22. The lower ends of the members 20—20 are pivoted by pivot pins 23—23 to tongues 24—24 that are rigidly mounted in the base 7. It is to be noted that the lower ends 25—25 of the 30 links 20 are outwardly flared. This serves two distinct purposes. First, it gives a wide base for the legs and, second, it allows the members 20—20 to straddle the members 14—14 and their mounting lugs 17—17 when the table is in its collapsed position, as illustrated in Figure 4.

When the table is in its extended position the three legs thereof are substantially vertical, the links 13-14 of each leg being in toggle position. They are held in toggle position by a releasable holding toggle 28 consisting of two links 29-30 of the same length, pivoted together at 31. The link 30 is pivoted to one of the members 14 of the associated leg by a pivot or dowel pin 32. The other link 29 is pivoted by a pin 33 to a tongue or lug 34 that is rigidly secured to the underside of the table. One toggle 28 may be provided for each of the three legs of the table although a single toggle for only one of the legs will hold the table against collapse. When the table is in its extended position the links 28-29 are in substantially their position of toggle, that is, the center of the pivot 31 is in line with the centers of the pivots 32-33.

Three small flat boards 35 are secured respectively to the undersides of the three radial bars 6. The edges 36 of the bars are in position to be abutted by the members 14 of the respective links 12. The toggle 28 holds the members 14 of the associated link 12 in firm pressure engagement with the edges 36 of the two adjacent boards 35. Therefore, if any play should develop at the holes for the pivot pins 18 of the links 12 the toggle link 28 will force the members 14 of the associated link 12 to fulcrum about the edge 36 of the board 35 and force the end of the link and the pivot pin 18 to the extreme position regardless of any play that may have developed in the hole provided for the pin 18.

Dowel pins 39-39 are provided in each of the members 20-20 of the lower link 13. These dowel pins serve as stops to limit the extent of unfolding of the links 12-13 of each leg, so that when the table is in its extended position the members 14-14 of each leg are supported by the two pins 22-22 and the two pins 39-39.

In order to fold the table it is merely necessary to break the toggles 28 of the respective legs by moving the associated toggle pivots 31 of the toggles downwardly. Each link 12 swings about the pivots 18-18 into engagement with the underside of the table top 1. At the same time the toggle links 29-30 move into position side by side between the members 14-14 of the link 12, and are covered by the board 15. As the links 12 of the respective legs are swinging about their pivots 18, each pivot 22 is swinging towards the underside of the table top, and the pivots 23 are moving towards the pivots 18. When the link 15 reaches its extreme folded position, illustrated in Figures 3 and 4, the members 20-20 of the link 13 embrace the members 14-14 of the link 12, and the ends 25-25 of the members 20 embrace and lie on the outside of the lugs 17-17 clearing those lugs by a small amount. At that time the base 7 overlies the pivotal connections between the links 12 and the table top, as may be seen from Figure 4.

It is to be noted, particularly in Figure 6, that the pivot pin 22 and the lug or stop 39 are positioned off center with respect to the center of the links. This is for the purpose of facilitating the folding action so that when the two links of the leg are folded the board 21 of the link 13 overlies and is parallel to the board 15 of the link 12. The tongues 24 of the base 7 are spaced from the lug 17 of the table top an amount sufficient for the ends 25 of the lower links 13 to clear the lugs 17 so that the tongues 24 may move substantially into contact with the underside of the table top when the table is folded. By this arrangement

the lower side of the base extends substantially flush with the lower side of the rim 2 when the table is folded, as may be seen from Figure 3. This produces a neat and compact arrangement which facilitates storage of the table. Furthermore, during storage of the table none of the pivots of the respective links are subjected to stress of the type that might injure the structure.

In the table herein illustrated the vertical distance between the pivots 18 and 22 is the same as the vertical distance between the pivots 23 and 22. Different relative lengths may be used. However, in order to facilitate folding of the table in the manner illustrated in Figure 3, the effective length of the link 12 plus the distance of the axis of the pivots 18 from the center 40 of the table is made equal to the effective length of the link 13 plus the distance from the pivot axis 23 to the center of the table. Thus if the link 12 is of the same effective length as the link 13 then the effective distance from the table center to the pivot axis 18 is made the same as the effective distance from the table center to the pivot axis 23. If the link 12 is made shorter than the link 13 then its pivot 18 is placed correspondingly farther from the center of the table. By this arrangement the folding action of the table is such that as the table top moves towards the bottom it is always parallel to the bottom 7.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A folding table including a table top, a base parallel thereto, a plurality of folding legs between the top and the base, each leg comprising a set of pivotally connected upper and lower links pivoted respectively to the top and to the base about fixed pivots, one of the links of each leg comprising a pair of members embracing the other link at the pivot between them, the two members of said one link being spaced apart throughout their length a distance sufficient to receive the other link of the same leg between them, said links of each leg being foldable from a collapsed side by side position substantially parallel to and embracing one another to an extended toggle position substantially in alignment with one another, means to limit the pivoting of the links in their unfolding direction, and releasable means for holding the links in their extended position, said releasable means being located between the base and the top and foldable into a position between them upon collapsing of the table.

2. A folding table including a table top, a base parallel thereto, a plurality of folding legs between the top and the base, each leg comprising a set of pivotally connected upper and lower links pivoted respectively to the top and to the base about fixed pivots, one of the links of each leg comprising a pair of members embracing the other link at the pivot between them, the two members of said one link being spaced apart throughout their length a distance sufficient to receive the other link of the same leg between them, said links of each leg being foldable from a collapsed side by side position substantially parallel to and embracing one another to an extended toggle position substantially in alignment with one another, stop means carried by one of

the links and cooperating with the other link to limit the pivoting of the links in their unfolding direction, and releasable means for holding the links in their extended position, said releasable means being located between the base and the top and foldable into a position between them upon collapsing of the table.

3. A folding table including a table top, a base parallel thereto, a plurality of folding legs between the top and the base, each leg comprising a set of pivotally connected upper and lower links pivoted respectively to the top and to the base, one of the links of each leg comprising a pair of members embracing the other link at the pivot between them, the two members of said one link being spaced apart throughout their length a distance sufficient to receive the other link of the same leg between them, said links of each leg being foldable from a collapsed side by side position substantially parallel to one another to an extended toggle position substantially in alignment with one another, releasable means for holding the links in their extended toggle position, and means urging the links of each leg out of the toggle position and against said releasable means to take up the free play at the link pivots.

4. A folding table including a table top, a base parallel thereto, a plurality of folding legs between the top and the base, each leg comprising a set of pivotally connected upper and lower links of equal lengths pivoted respectively to the top and to the base, one of the links of each leg comprising a pair of members embracing the other link at the pivot between them, the two members of said one link being spaced apart throughout their length a distance sufficient to receive the other link of the same leg between them, the links of the legs being pivoted to the top and to the base about pivot axes spaced the same distance around a common center, whereby the base and the table top remain parallel to one another throughout the folding and unfolding of the table, said links of each leg being foldable from a collapsed side by position substantially parallel to one another to an extended toggle position substantially in alignment with one another, stop means carried by one of the links and cooperating with the other link to limit the pivoting of the links in their unfolding direction, and releasable means for holding the links in their extended position, said releasable means being located between the base and the top and foldable into a position between them upon collapsing of the table.

5. A folding table including a table top, a base parallel thereto, a plurality of folding legs between the top and the base, each leg comprising a set of pivotally connected upper and lower links pivoted respectively to the top and to the base about parallel axes, one of the links of each leg comprising a pair of members embracing the other link at the pivot between them, the two members of said one link being spaced apart throughout their length a distance sufficient to receive the other link of the same leg between them, the pivot axes of the respective legs to the top and to the base being spaced around a common center with the axes of some of the legs at an angle to the axes of other of the legs, whereby the base and the table top remain parallel to one another throughout the folding and unfolding of the table, said links of each leg being foldable from a collapsed side by side position substantially parallel to one another to an extended toggle position substantially in alignment with

one another, stop means carried by one of the links and cooperating with the other link to limit the pivoting of the links in their unfolding direction, and releasable means for holding the links in their extended position, said releasable means being located between the base and the top and foldable into a position between them upon collapsing of the table.

6. A folding table including a table top, a base parallel thereto, a plurality of folding legs between the top and the base, each leg comprising a set of pivotally connected upper and lower links pivoted respectively to the top and to the base, one of the links of each leg comprising a pair of members embracing the other link at the pivot between them, the two members of said one link being spaced apart throughout their length a distance sufficient to receive the other link of the same leg between them, the links of the legs being pivoted to the top and to the base about pivot axes spaced around a common center, in each leg the length of the link that is pivoted to the table top plus the distance of its top pivot from the common center being the same as the length of the other link plus the distance between its base pivot and the common center, whereby the base and the table top remain parallel to one another throughout the folding and unfolding of the table, said links of each leg being foldable from a collapsed side by side position substantially parallel to one another to an extended toggle position substantially in alignment with one another, stop means to limit the pivoting of the links in their unfolding direction, releasable means for holding the links in their extended position, said releasable means being located between the base and the top and foldable into a position between them upon collapsing of the table, and means urging the links of each leg out of the toggle position and against said releasable means to take up the free play at the link pivots.

7. A folding table comprising a table top, a base, a plurality of legs between the top and the base, each leg comprising an upper link pivoted to the table top, a lower link pivoted to the base, means pivotally connecting the upper and lower link of a leg together, the two links of each leg being substantially in toggle position when the table is unfolded, one of the links of each leg comprising a pair of members embracing the other link at the pivot between them, the two members of said one leg being spaced apart throughout their length a distance sufficient to receive the other link of the same leg between them, said links of each leg being foldable to a collapsed side by side position substantially parallel to and embracing one another.

8. A folding table including a table top, a base parallel thereto, a plurality of folding legs between the top and the base, each leg comprising a set of pivotally connected upper and lower links pivoted respectively to the top and to the base, one of the links of each leg comprising a pair of members embracing the other link of the leg, said links of each leg being foldable from a collapsed side by side position substantially parallel to one another to an extended toggle position substantially in alignment with one another, and releasable means associated with only one of the legs for holding the links of that one leg in their extended toggle position, said one held leg acting through the base to prevent the folding of the other legs out of their extended toggle positions.

9. A table including a plurality of folding legs each of which comprises a set of pivotally connected upper and lower links, one of the links of each leg comprising a pair of members embracing the other link of the same leg at the pivot between them, the two members of said one link being spaced apart throughout their length a distance sufficient to receive the other

link of the same leg between them, said links of each leg being foldable from a collapsed side by side position substantially parallel to and embracing one another to an extended toggle position substantially in alignment with one another, and releasable means for holding the links of the legs in their extended positions.
